UNITED STATES PATENT OFFICE.

GEORGE H. GEYER, OF PITTSBURG, PENNSYLVANIA.

MACHINE FOR STRAIGHTENING T-BARS, ANGLE-BARS, &c.

SPECIFICATION forming part of Letters Patent No. 731,675, dated June 23, 1903.

Application filed August 27, 1902. Serial No. 121,230. (No model.)

To all whom it may concern:

Be it known that I, GEORGE H. GEYER, a citizen of the United States, residing at Pittsburgh, in the county of Allegheny and State of Pennsylvania, have invented or discovered certain new and useful Improvements in Machines for Straightening T-Bars, Angle-Bars, &c., of which improvements the following is a specification.

10 The invention described herein relates to certain improvements in machines for straightening T's and angle-bars, and has for its object a construction whereby the desired flexure or bending of the bar necessary to straighten it can be applied thereto and all parts of the bar rigidly supported as against distortion during such flexure and bending.

The invention is hereinafter more fully described and claimed.

20 In the accompanying drawings, forming a part of this specification, Figure 1 is a sectional elevation of my improved straightening-machine. Fig. 2 is a side elevation of the same. Fig. 3 is a sectional plan view, the upper rolls and their cradles being removed. Figs. 4, 5, 6, and 7 are detail views of the cradles and the rolls carried thereby, and Fig. 8 is a detail illustrating the manner of straightening angle-bars.

30 In the practice of my invention the frame of the machine consists of a bed-plate 1 and a supporting-housing 2, the parts of the housing being connected transversely by suitable bars 3, as shown in Fig. 1. The bed-plate is provided with suitable guide-ribs 4, forming bearing-surfaces for the cradles carrying the lower rolls, as hereinafter described. Each of the cradles consists of a bottom portion and vertical side portions 5^a and 5^b, and as it is preferred that the cradles on each side should be adjusted equally it is preferred that the cradles should be connected. For convenience of construction and erection the cradles are made independent and are connected by

40 means of bolts passing through flanges 6, formed on adjacent edges of the sides 5^a. As clearly shown in Figs. 1, 3, 6, and 7, the cradles are provided with bearings 7 for the journals of the rolls 8, and on one of the journals, preferably the lower one, are secured beveled pinions 9, adapted to intermesh with

correspondingly-shaped pinions 10 on the driving-shafts 11, whereby the several lower rolls are driven in unison. It will be observed that the bearings 7 are so constructed on the sides 5^a and bottom 5 of each cradle that the rolls have their axes at an angle of about forty-five degrees to a horizontal plane, and a collar 8^a is formed on each of the rolls, said collar being formed at such an angle to the axes of the rolls as to form a horizontal bearing-face for the flange of the T's or one side of the angle to be straightened. In order to effect a transverse flexure of the flange portion of the T's or one side of the angle-bars to straighten the same, each of the rolls 8 is provided with a collar 8^b, which will bear against the edges of the flanges and impart the necessary transverse flexure. By reference to Fig. 3 it will be seen that adjacent rolls have their axes at right angles to each other or have opposite inclinations, so that the shoulders 8^b on one roll will act in opposition to the corresponding shoulder on the opposite roll. By reference to Fig. 3 it will be seen that bottom portions 5 and side portions 5^b of the cradles are sufficiently narrow to permit of such portions of the cradles on one side to overlap corresponding portions of the cradles on the opposite side of the machine, and that the cradles are so arranged that rolls carried by the cradles on one side will alternate with those on the other side. Provision is made for the adjustment of each of the cradles transversely of the bed of the machine in opposite directions. A convenient construction to this end consists of a brace-bar 12, secured to the housings, and screws 13, passing through the brace-bar and bearing against the cradles. Similar cradles, each provided with bearings 14, are suspended from the horizontal portion of the housing by means of screws 15, which engage undercut grooves in the cradles, so as to permit a lateral adjustment of the cradles, as hereinafter described. The bearings for the rolls are so constructed that the axes of the rolls will be at or approximately at an angle of forty-five degrees with the horizontal plane and the rolls are provided with collars, having faces 16 and 17 formed at right angles to each other. These faces are adapted to bear upon

the inner faces of the flanges and the side faces of the stems of the T's and against corresponding portions of angle-bars, so as to maintain such portions in proper alinement. 5
 5 A lateral adjustment of the cradles and the rolls can be effected in any convenient manner—such, for example, as that shown, consisting of screws 18, passing through the brace-bars 12, heretofore described, and bearing 10 upon the sides of the cradles. The upper cradles are so supported that the rolls 14 alternate with each of the lower rolls 8. It will be observed that each of the bearings is provided with suitable oil-pockets 19, having 15 outlets therefrom to maintain the journals and bearings in a suitably-lubricated condition. For convenience in construction it is preferred that each of the upper cradles should be formed in sections connected by 20 suitable bolts, as clearly shown in Figs. 4 and 5.

It will be clearly understood by those skilled in the art that the several parts of the straightening-machine and the faces of the rolls are so constructed and arranged that 25 all portions of the T's and angle-bars will be supported during the straightening operation and that by the suitable adjustment of the cradles any desired or necessary flexure may be imparted to the T's and angle-bars in order to bring them into the desired condition.

I claim herein as my invention—

1. In a machine for straightening T's, angle-bars, &c., a combination of a series of three or more rolls, each having bearing-faces 35 at an angle to each other, said rolls being arranged to bear on different portions of the article in succession, and means for adjusting said rolls toward and from a common line, substantially as set forth.

40 2. In a machine for straightening T's, angle-bars, &c., the combination of two series of lower cradles having rolls mounted therein, the cradles of one series alternating with those of the other series; two series of upper 45 cradles having rolls mounted therein and alternating with the cradles of the lower series,

and means for adjusting the several cradles, substantially as set forth.

3. In a machine for straightening T's, angle-bars, &c., the combination of two series 50 of lower rolls each provided with bearing-faces at or approximately at right angles to each other, the rolls of one series alternating with and arranged in opposition to those of the other series, upper rolls having bearing-faces at right angles to each other, said rolls 55 alternating with the lower rolls and arranged to act in opposition thereto, substantially as set forth.

4. In a machine for straightening T's, angle-bars, &c., the combination of two series of lower rolls each provided with bearing-faces at right angles to each other, the rolls of one series having their axes at or approximately at right angles to the axes of the rolls 65 of the other series, upper rolls having bearing-faces at right angles to each other, one or more of the upper rolls having their axes parallel with the axes of the rolls of one of the lower series, and the other upper rolls having their axes parallel or approximately so to the axes of the rolls of the other lower series, and means for adjusting the several rolls, substantially as set forth.

5. In a machine for straightening T's, angle-bars, &c., the combination of a housing 75 two series of cradles oppositely mounted in the housings, rolls drawing suitable bearing-faces angularly arranged in the cradles, upper cradles adjustably suspended in the housing, rolls having suitable bearing-faces angularly arranged in said housing, brace-bars secured to the housing and screws passing through the brace-bars and bearing against the cradles, substantially as set forth.

In testimony whereof I have hereunto set my hand.

GEORGE H. GEYER.
